UNITED STATES PATENT OFFICE.

PAUL A. DE LEON, OF BAYONNE, NEW JERSEY, ASSIGNOR TO THE CLOTHEL COMPANY, OF NEW YORK, N. Y., A CORPORATION OF NEW YORK.

MEANS FOR BORING OR REAMING.

1,264,492.

Specification of Letters Patent. Patented Apr. 30, 1918.

Application filed September 25, 1916. Serial No. 121,948.

To all whom it may concern:

Be it known that I, PAUL A. DE LEON, a citizen of the United States, and resident of Bayonne, in the county of Hudson and State 5 of New Jersey, have invented certain new and useful Improvements in Means for Boring or Reaming, of which the following is a specification.

This invention relates to new and useful 10 improvements in means for boring or reaming to produce a bore or chamber of irregular contour. The invention will be found useful in various arts, but especially in the formation of substantially elliptical piston 15 chambers for rotary piston pumps, compressors, engines and similar devices employing rotary pistons each turning on an axis eccentric to its chamber and provided with sliding radial piston blades which coöperate 20 with a wall of the chamber.

The invention consists in the improvements to be hereinafter more fully described.

The embodiment of the invention illustrated in the drawings is adapted to ream 25 the inner face of a true cylinder in such a manner that when a rotor is eccentrically journaled in the cylinder a line extending through the center of the rotor and touching the casing at opposite points will be of the 30 same predetermined length wherever drawn.

In the drawings Figure 1 is a top plan view, partly in section, illustrating a compressor casing held in position for reaming; the reaming means being shown in working 35 position within the casing;

Fig. 2 is a sectional view on the line 2—2 of Fig. 1;

Fig. 3 is a sectional view on the line 3—3 of Fig. 2;

Fig. 4 is a plan view, partly in section, of the reaming means;

Fig. 5 is an elevation of the device shown in Fig. 4; and

Fig. 6 is a diagrammatic view illustrating 45 the action of the invention in the facing of a rotor cylinder.

Referring to the drawings, 2, designates a work support constructed to hold the element to be subjected to the action of my invention and which may also, if desired, serve as a bearing support for the boring or reaming means. This support 2 may be constructed in a variety of ways without departing from my invention. It may, for instance, consist of a table or platform sup-

ported upon suitable legs 3 and formed with a peripheral vertical flange 4 providing a seat 5 to receive the end flange of the work. The work support is also provided with vertical abutments or rests 6, against which the 60 wall of the work casing is permitted to abut, whereby the work is held against rotative movement when being operated upon.

Carried by or forming a part of the work support just described is a bearing support 65 which may consist of connected arms 7 formed with a central aperture to receive a vertically disposed bearing 8, which bearing is so located as to be eccentric of the internal bore of the work when the latter is supported 70 in position on the work support.

The boring or reaming means comprises a cylindrical bar 9 adapted to turn in bearing 8 and being journaled slidably through the latter; said bar carrying a head 10, from 75 which rises a shank 11 adapted to be engaged by the mandrel of a drill press or other rotary means whereby the said shank 11, head 10 and bar 9 may be rotated.

The head 10 is formed with a transverse 80 opening 11^x the central longitudinal axis of which extends at right angles to the longitudinal axes of the head 10 and the bar 9. The opening 11^x is preferably cylindrical in cross section and contains a split bearing 85 sleeve comprising the parts 12, 13, one of which, 12, is held in place against turning and also lengthwise movement by key pins 14, seated in aligned openings formed in the wall of head 10 and the said bearing sleeve 90 part. The other part 13 of the split sleeve is held in place by set screws 17 extending through the side wall of the head 10 within recesses 18 formed in said part 13. Lock nuts 19 may be provided on the set screws 95 17 to hold them in adjusted position. Reciprocable through the bearing provided by the parts 12, 13 is a tool carrier 20, preferably in the form of a cylindrical bar, one end of the bar being provided with a slot 100 or recess 21 to receive a cutting tool 22, which may be held in position in said slot by a set screw 23. This cutting tool is set to extend at right angles across the internal cylindrical face of the work and in order that it may 105 be so held and the bar 20 prevented from turning, said bar is keyed to the bearing part 12 by key 24.

On its end opposite that carrying the cutting tool, the bar is provided with a fol- 110

lower constructed and arranged as follows: On the end of the bar is a head or enlargement 27, formed with a socket 28 (Fig. 3) in which is slidably held a block 29, said block being held against rotation by fins or webs 30 on the opposite sides thereof and slidably fitted within grooves 31, formed in the opposite walls of the chamber 28. In order to adjust and hold the block 29 at the proper point, I provide an adjusting and holding screw 32, threaded at one end in a threaded aperture 33 formed in the block and having its opposite end rotatively seated in a bearing recess 34 in the bottom 15 of the socket 28. The screw 32 is provided with an intermediate recessed flange 35 adapted to be engaged by a pin wrench (not shown) and to be rotated thereby to effect the desired adjustment of the block, the wall 20 or socket 28 being cut away for such purpose, as shown in Fig. 1. The flange 35 may be engaged by any suitable locking means to hold the screw against accidental rotation, for instance the said flange may be provided with recesses adapted to be engaged by a spring pawl 35^a, as indicated in dotted lines in Fig. 2.

The outer end of block 29 is provided with a semi-cylindrical groove or recess 38 to receive a wear piece or contact piece 39 having a substantially flat outer piece adapted to contact with the internal cylindrical face of the work. This contact piece is held against movement lengthwise of itself by means of keeper plates 40, secured by screws 41 to the upper and lower faces of the block 29, as shown in Figs. 1 and 2 of the drawings.

Fig. 6 diagrammatically illustrates the action of the present embodiment of the invention in facing the cylindrical bore of a rotor casing so that the latter is made quasi-elliptical. In said figure *a* indicates the longitudinal axis of the casing bore, while *d* illustrates the offset position of the mandrel axis, which, when the facing is completed, becomes the axis of the rotor. For purposes of illustration the cylinder has been divided by two sector lines *c* and *c'*. Now when the 45 mandrel is turned so that the longitudinal axis of the carrier lies in the sector line *c'*, the carrier is movable across the axis of the cylinder. It is in this position that the follower 29 is adjusted for the first cut, it being manifest that whenever the axis of the rotor is to be substantially offset from the axis of the casing the thickness of the metal to be cut away from the cylindrical casing makes it necessary or advisable to effect the 50 facing by a plurality of cuts. Assuming that in the position indicated, the blade and follower both contact with the wall of the casing, the follower is moved inwardly a distance proportionate to the desired depth 55 of the first cut, and the mandrel is then

rotated and fed axially to carry the tool through the work, the resulting cut being indicated at *e* in Fig. 6. In the facing operation illustrated in the figure three successive cuts are made. Now preliminary to the second cut, the follower is moved forwardly a distance equal to the desired cut at its maximum depth point; the second cut being indicated at *f* on Fig. 6. Preliminary to the third and final cut, the mandrel is turned 70 until the longitudinal axis of the carrier 20 lies in the sector line *c'*, and then the follower is adjusted forwardly until both the tool and the follower contact with the wall of the casing. After the formation of 75 the third cut *g* lines drawn in any direction through the mandrel axis and touching at their ends the casing wall, will be of equal 80 length.

To insure that the tool will be held out of 85 contact with the casing wall when the carrier turns out of normal cutting position a spring, or springs, such as 42 may be arranged to act continuously on the carrier 20 in such manner as to move cutting tool 22 90 rearwardly and away from the casing wall. In the present embodiment of the invention each spring is fitted in a socket 43 formed 95 in the mandrel head 10 the stress of the spring acting upon a contact stud 44 tapped into the wall 27 of the carrier. To hold the spring in position throughout the reciprocation of the carrier a guide pin 45 is secured at one end to each contact stud 44 and extends through the socket and an aperture in 100 the bottom wall of the latter.

It is manifest that various changes and modifications may be made in the embodiment herein described and illustrated without departing from the spirit of the invention, and therefore I do not limit myself to said embodiment except in so far as required by the scope of the claims, but what I claim is as follows:

1. In means for boring or reaming the 110 combination with a work support of a rotary mandrel formed with a transverse aperture, a tool carrier supported in said aperture and free for endwise movement therein, a tool carried by said carrier at one end thereof 115 and a non-cutting contact member at the opposite end of said carrier.

2. In means for boring or reaming, the combination with a rotary mandrel, of a work support adapted to hold a casing to be 120 operated upon, means for supporting the mandrel eccentrically of the longitudinal axis of the casing bore, a tool carrier held for endwise movement upon the mandrel, a tool held at the end of the carrier, and a 125 follower held at the opposite end of the carrier.

3. In means for boring or reaming, the combination with a rotary mandrel, of a work support adapted to hold a casing to be 130

operated upon, means for supporting the mandrel eccentrically of the longitudinal axis of the casing bore, a tool carrier held for endwise movement upon the mandrel, a tool held at the end of the carrier, and a follower held at the opposite end of the carrier, said follower being adjustable to increase the effective length of the tool carrier.

4. In means for boring or reaming, in combination, a work support formed with a bearing aperture, a mandrel journaled in said bearing aperture, seats on the work support adapted to hold a casing with its longitudinal axis eccentrically disposed with respect to the longitudinal axis of the mandrel, a tool carrier supported upon the mandrel for reciprocation transversely thereof, a follower at one end of the carrier, and a tool at the opposite end of the carrier.

20 5. In means for boring or reaming, in combination, a mandrel, a cutting tool sup-

ported upon the mandrel and free for movement transversely of the longitudinal axis of the latter, and a spring engaging the cutting tool and tending to press the same rearwardly while permitting a reverse movement thereof.

6. In combination, a work support for supporting an annular body, a member rotatable on an axis eccentric to that of said body, a cutter bar carried by said member and slidable transversely thereof, said bar carrying at one end a cutter and at the other end a follower to respectively contact the interior face of said annular body.

In testimony whereof I have hereunto signed my name in the presence of two subscribing witnesses.

PAUL A. DE LEON.
